(57) CLAIM

The ornamental design for diamond shaped makeup applicator as shown and described.

DESCRIPTION

FIG. 1 is a front isometric view of the diamond shaped makeup applicator, showing my new design;

FIG. 2 is a bottom view, the top view shall be identical thereof;

FIG. 3 is a right-side view, the left-side view shall be identical thereof;

FIG. 4 is a front view thereof; and,

FIG. 5 is a rear view thereof.

The broken lines in all the figure views are for illustrative purposes only and form no part of the claimed design.
